F. C. DUDLEY,
AUTOMATIC STERILIZING INSTRUMENT CASE,
APPLICATION FILED JAN. 31, 1917.

Patented Oct. 8, 1918.

Inventor
F. C. Dudley

By William H. Bates

Attorney

UNITED STATES PATENT OFFICE.

FRANK C. DUDLEY, OF BROOKLYN, NEW YORK.

AUTOMATIC STERILIZING INSTRUMENT-CASE.

1,280,687.

Specification of Letters Patent.

Patented Oct. 8, 1918.

Application filed January 31, 1917. Serial No. 145,595.

To all whom it may concern:

Be it known that I, FRANK C. DUDLEY, a citizen of the United States, residing at Brooklyn, in the county of Kings and State 5 of New York, have invented certain new and useful Improvements in Automatic Sterilizing Instrument-Cases, of which the following is a specification.

My invention has relation to improvements in the casing of surgical instruments as hypodermic syringes or clinical thermometers, and the object of the invention is to provide suitable means for immersing the instrument or syringe in an antiseptic solution in connection with a spring valve action within the casing. With these ends in view the invention consists in the novel construction and combination of the several parts as will be hereinafter more in detail described and the asserted novelty specifically claimed.

I have fully and clearly illustrated my invention in the accompanying drawings in which,

Figure 1 represents a sectional elevation showing the spring depressed in the casing and the needle of a hypodermic syringe lowered.

Fig. 2 represents the valve spring located in the lower part of the casing, also a filling of lamb's wool or similar material in a relaxed position. Fig. 3 is a detail view.

Referring more in detail to the drawings, A designates a casing of peculiar construction comprising a long tubular section, having windows *a* and a shorter section of glass tubing *a'*, the latter telescoping within the former.

B designates a coiled spring located near the lower end and within the casing, said spring being expanded or relaxed as clearly shown in Fig. 2.

C designates a graduated hypodermic syringe also within the casing of that class usually employed for hypodermic injections, and therefore the construction being *per se* old and forming no part of my invention, a further description of which is herein deemed unnecessary.

D designates a filling of suitable porous

material preferably lamb's-wool located in the lower portion of the longer section *a* of the casing and in which a spring valve action is produced conjointly with the lamb's-wool, a solution, and spring E designates a 55 short slideable tube, one end the lower end of this tube is seated on the upper end of the spring B, supporting the lamb's-wool and said tube being operated by the aforesaid spring. When the casing is filled with two 60 drams of antiseptic solution as 70 per cent. of alcohol this solution, when the spring is pressed down as shown in Fig. 1, comes up above the porous material of lamb's-wool, and when the syringe is removed the spring 65 raises the lamb's-wool up and creates a suction which draws all of the solution below, making or performing a spring valve action, as hereinbefore stated, so that the solution will not leak out even if the casing is inverted, or positioned in any manner. This 70 spring valve action I deem as of the first importance as it can be used in thermometers and all other instruments of a like character to which it may be adapted, 75 and it is desired to be understood that I do not confine myself to hypodermic syringes *per se*, but, as previously stated, all other instruments of a like character.

The shorter section or cap of the casing 80 may be conveniently placed on the opposite end of the case, if desired. The syringe can be carried in the pocket, and is always sterile and ready for use.

What I claim as new and desire to secure 85 by letters patent, is:

The combination with a sectional casing of a coil spring mounted in the lower portion thereof, wool or like substance mounted on the upper end of the spring and a tube 90 resting on and compressing the wool when the tube is depressed by inserting a syringe within the sectional casing.

In testimony whereof I affix my signature in the presence of two witnesses.

FRANK C. DUDLEY.

Witnesses:

GERARD R. KERN,
RUTH N. JUBELT.
